Diehl assignor to said Rautiola

Continuation of application Ser. No. 348,724, Mar. 2, 1964, which is a continuation-in-part of application Ser. No. 253,893, Jan. 25, 1963. This application Sept. 24, 1965, Ser. No. 495,014

2 Claims. (Cl. 128—1)

ABSTRACT OF THE DISCLOSURE

An acoustic device in conjunction with a stuffed toy or the like which provides for soothing and tension relief of sleep centers to promote sleep, the acoustic stimuli being in the range of 60 to 400 c.p.s.

This application is a continuation of application Ser. No. 348,724, filed Mar. 2, 1964, now abandoned having the same entitlement, which application is a continuation-in-part of application Ser. No. 253,893, filed Jan. 25, 1963, now abandoned entitled Doll to Tranquillize Infants.

This application relates to a doll and more particularly to a doll provided with means for emitting an audible signal having certain pre-selected characteristics.

The doll may have any desired form, such as that of a baby or a small girl or that of a Teddy bear or other animal. The doll may be made of plastic or rubber if in the human form, and may be articulated in any desired fashion. If in the form of an animal, the doll may be stuffed and provided with a fuzzy covering to provide a soft and cuddly device, or may be made of rubber or polyethylene or other plastic in order to be soft, unbreakable, washable and resilient.

As an essential and critical feature of the invention, there is incorporated within the doll a device which emits sound waves having a frequency of from 100 to 350 cycles per second or usefully 60-400 cycles per second. A doll may be provided with means to cause such a signal to be emitted at all times or may be provided with means to cause such signal to be emitted only upon operation of a switch by an adult or upon the proximity of the doll to a human person.

The cuddly toy such as a stuffed animal or doll cooperates with the acoustic signal to create a more restful environment for the infant.

It is an object of the invention to provide a doll which will be popular with adults and infants alike by reason of lulling to sleep readily an infant or small child who possesses the doll. That is, it is an object of the invention to provide a doll which causes an infant or small child possessing the doll to be relatively tranquil despite any tendency of the child to be irritable in the absence of its possession of the doll.

Other objects will become apparent from the drawings and from the following detailed description in which it is intended to illustrate the applicability of the invention without thereby limiting its scope to less than that of all equivalents which will be apparent to one skilled in the art. In the drawings like reference numerals refer to like parts and:

FIGURE 1 is a perspective partially cut-away view of the device of the invention;

2

FIGURE 2 is a schematic cross-sectional view of a modified form of the embodiment of FIGURE 1, in which a switch is provided for operation of the means for producing an audible signal;

5 FIGURE 3 is a modification of the embodiment of FIGURE 1 wherein there is provided means for causing an audible signal to be emitted from the doll when the doll is in close proximity to a human;

FIGURE 4 is a graph of some suitable signals.

10 Use of the device of the invention by a crying baby has the immediate effect on the subject of producing quiescence and relaxation comparable to that exhibited by an infant when picked up by a parent. This is accomplished relatively quickly and sleep usually follows in from 30 seconds to 5 minutes. The calming effect is sufficient so that once the infant is asleep the device may if desired, be turned off or removed and yet the infant will remain asleep.

15 Referring now to FIGURE 1 there is shown a doll indicated generally as 1. The doll may have a fabric covering 2, and it may be stuffed with excelsior, cotton linters or other textile by-products 3. Imbedded in an 20 supported by stuffing 3, there is provided an oscillator unit 4 which may comprise within a suitable housing a power source such as a battery and also a circuit preferably transistorized and, if desired, one amplifier stage 25 preferably transistorized. The output of oscillator unit 4 is a signal in the range of preferably 100 to 325 cycles per second of sufficient amplitude to drive speaker 5 with which unit 4 is connected by wire 6.

30 In FIGURE 2 there is shown another embodiment wherein a toy doll indicated generally as 10 may comprise a shell 12 of soft plastic such as polyethylene or polyvinylchloride or of soft rubber. The doll made of such material may be suitably manufactured by use of slush-molding, blow-molding or injection molding techniques as may be desired. Attached to the interior surface portion of shell 12 there is provided oscillator unit 14 which may suitably comprise a power-pack such as one or more batteries, an oscillator circuit and, if desired, an amplifier. The output of unit 14 is fed through wire 16 to speaker 15, being of sufficient amplitude to suitably drive speaker 15. Speaker 15 may be attached to shell 12; a suitable opening as indicated at 15' may be provided in the shell to provide for a relatively sufficient emission of sound from the speaker. Oscillator unit 14 may suitably be provided with a switch 17 which, if desired, may extend as shown through shell 12. Switch 14 may be utilized to turn unit 14 on or off by suitably interrupting a circuit therein and may be operated by an adult or by a child-user of the device. The switch may suitably be opened to prevent undue drain on the battery power source and may be closed to cause the unit 14 to operate and speaker 15 to emit an audible signal to tranquilize a child or infant within the range of the device which is preferably about no less than 4 feet.

35 Referring now to FIGURE 3, there is shown a toy animal indicated generally as 20 which may simulate a common animal such as a dog, kitten or lamb and may be made in the manner of FIGURE 1 in order to be provided with a fluffy outer surface or if desired may be made, as shown, by blow-molding, slush-molding, injection-molding or other suitable techniques to provide shell 22 of soft material which may be a plastic such as polyethylene or polyvinylchloride or may be a soft rubber. Attached to the interior of the toy 20 in any suitable manner (such as in the manner shown, by attachment to

the interior surface of shell 22) there may be provided oscillator unit 24. A suitable housing 24 may contain a power source, an oscillator circuit and, if desired, one or more amplifier stages to drive speaker 25 to cause the speaker to emit an audible signal. Instead of being spaced part as individual units, speaker 25 and oscillator unit 4 may be provided as an integral unit as shown. The two can be attached together and by attachment of any portion of either to any portion of the toy they may be held suitably in place. Attached to shell 22 or otherwise suitably located on or within toy 20 there may be provided a switching device 27 which may be suitably connected by wires 28 into a circuit of unit 24 to cause the circuit to be interrupted when the toy is not in close proximity to a person and to cause the circuit to be closed when the toy is within a certain desired distance of a human person, say 6 inches. Such a switch may operate by reason of a change in capacity produced between two capacitative members by the presence of a human or in any other conventional manner. Such switches are commonly used to operate elevators by merely placing a hand or finger against the switch. Another suitable switch may be a switch in which there is included means which are sensitive to infrared radiation and thereby adapted to detect the presence of a human by reason of the infra-red rays emitted by a human. Such means may incorporate an element or compound sensitive to infra-red radiation, such as, for example, silicon, germanium or compounds of the III-V elements of the Periodic Table such as for example indium arsenide and indium antimonide. The device may be suitably adjusted to provide for creation of a sufficient signal to actuate a switch to turn on the sound emitting device only when the doll is in relatively close proximity to a human, preferably within two feet of a human. A thermocouple may be used as an infra-red sensitive device if suitable means for focusing the infra-red radiation is provided to cause a relatively large amount of it to fall on the relatively small thermocouple surface. Said switches are of particular usefulness in that sound is emitted by the doll only when it is in close proximity to a human or an animal; thus when placed in such close proximity the sound emitter will be actuated and when the device is removed from such close proximity the sound emitter is automatically deactivated.

In unpreferred embodiments of the invention, the invention may be applied to objects other than dolls or toy animals and in fact may be applied to any object in close physical proximity to a sleeping infant, such as, for example, a pillow, a bed frame, a mattress, a covering such as a comforter or blanket, or the like. In accordance with such unpreferred embodiments, a noise emitting device of any one of the above embodiments may be introduced into the interior of such an object, that is, may be introduced into the interior of a mattress or a pillow or quilt or comforter or the like.

Although the device of the invention has its greatest utility in its application to infants, variations of the device of the invention may be applied in soothing and facilitating sleep of older children or adults or animals.

As signals, monotones repeated at uniform intervals at frequencies of 101 cycles per second and 325 cycles per second have been found particularly suitable for use in a device of the invention, but whereas, a sound emitting device adapted to emit such a signal when embodied in a doll has been found particularly suitable in accomplishing the object of the invention, the signal is not normally attractive to an older child or an adult. Comparable results may be obtained by use of signals which simulate or duplicate the noise of waves gently lapping on a shore or beach; the noise of a breeze gently blowing through trees; the noise of rain on a roof; the noise of a steadily operating automobile, train or airplane; the noise of a clock ticking, or signals having forms shown in FIGURE 4.

FIGURE 4 is a graph of three signals, each of which

is suitable. In the case of signal 110 (tri-tone), the tone or pitch of the signal has three frequencies successively in a preselected pattern. These occur respectively as a lower tone, a middle tone, and the lower tone again. The signal 111 (broad tone) varies continuously from a lowest frequency to a highest frequency and thence to an intermediate low frequency, thence to an intermediate high frequency and then returns to said lowest frequency. Signal 112 (broad tone saw tooth) varies in frequency in a multiplicity of steps, beginning, for example, with a lowest tone and continuing through seven steps to a highest tone and thence returning in seven steps to said lowest tone. The number of steps, however, may be suitably varied. These signals having a fundamental frequency of 60-400 c.p.s. are more pleasing to the adult ear than a single acoustic signal, and are therefore more desirable.

In a preferred embodiment, the signal comprises two components, the first being a monotone, repeated at uniform intervals at a frequency of from 60 to 400 cycles per second and the second component being one of the aforementioned noises which simulates an artificial or natural phenomena.

The signal is preferably emitted for a period of at least 1 minute and preferably for a period of 2 minutes, 25 at a substantially constant average amplitude. The amplitude may vary from cycle to cycle or from micro-second to micro-second, but it is preferred that the amplitude average over any 5 second period or 30 second period be equal to that over any other 5 second period or 30 second period.

A noise simulating a purring of a cat may be suitable for a second component. Other suitable signals for a second component may be white noise, softened white noise, or music of a soothing or lullaby type.

It may thus be seen that the invention is broad in scope and includes such modifications as will be apparent to those skilled in the art and is to be limited only by the claims.

Having thus described our invention, we claim:

- 40 1. In a doll comprising a torso, head and limbs, the combination within the torso of:
  - means to emit an audible signal wherein said means comprises;
  - a source of electric power comprising at least one battery cell;
  - 45 means supplied with power from said source to generate an electrical signal having
    - a first electrical signal component and
    - a second electrical signal component and
  - 50 means to convert said electrical signal to an audible signal and emit the resulting signal as sound which may be heard by a nearby observer,
  - 55 wherein said first and second components are present simultaneously and
  - wherein said first component is a uniformly repeated monotone having a frequency of from 60 to 400 cycles per second.
2. In a doll comprising a torso, head and limbs, the combination within the torso of:
  - means to emit an audible signal wherein said means comprises;
  - a source of electric power comprising at least one battery cell;
  - 60 means supplied with power from said source to generate an electrical signal having
    - a first electrical signal component and
    - a second electrical signal component and
  - 65 means to convert said electrical signal to an audible signal and emit the resulting signal as sound which may be heard by a nearby observer,
  - 70 wherein said first and second components are present simultaneously and
  - wherein said first component is a uniformly repeated monotone having a frequency of from 60 to 400 cycles per second and

5
 wherein said second component is a simulation of a
 multitone multifrequency natural noise.
